UNITED STATES PATENT OFFICE.

ADOLPH SUCK, OF BOSTON, MASSACHUSETTS.

GATE FOR COAL-POCKETS.

No. 882,804.

Specification of Letters Patent. Patented March 24, 1908.

Application filed February 13, 1907. Serial No. 357,136.

To all whom it may concern:

Be it known that I, ADOLPH SUCK, of Boston, in the county of Suffolk and State of Massachusetts, a citizen of the United States, have invented a new and useful Improvement 5 in a Gate for a Coal-Pocket, of which the following is a specification.

The purpose of my invention is to provide an outlet and gate for a coal pocket which 10 may serve the purpose both of a discharge and of a screen so that the coal as it falls from the pocket has the dust and small matter screened out of it during its discharge, means being also provided to shut off the 15 supply of coal as occasion may require. When so arranged the embodiment of my invention shown in the drawings is especially useful for hard or anthracite coal. When, however, soft or bituminous coal is to be dis- 20 charged, the screen can be removed and the outlet enlarged if thought best.

My invention will be understood by reference to the drawings in which—

Figure 1 is a vertical section of an apparatus embodying my invention and arranged 25 for use with hard coal. Fig. 2 is a plan, a part being broken away to show the interior construction, and Fig. 3 is a vertical section corresponding to that of Fig. 1, the screen 30 being removed, the apparatus being arranged for use with soft coal.

A is the floor of the pocket from which extends downward through an opening therein a vertical chute B. A shelf C, C¹ extends 35 part way across the passage in the chute and practically closes the outlet therefrom, forming a narrow mouth c through which the coal issues. The portion C¹ of this shelf may be removed to enlarge the mouth c as is usually 40 necessary when the device is to be used for soft coal. Below the shelf C and extending from the opposite wall of the chute is a removable screen D having openings of proper size to screen out the smaller particles and 45 dust from the coal as it moves out of the pocket. The shelf C, C¹ and the screen D are at an angle to each other, the lower end C¹ of the shelf approaching the upper end of the screen D so as to form a narrow outlet d for 50 the coal. A discharge opening from the chute is provided on the side B¹ thereof and above the lower edge of the screen. The arrangement of the shelf and screen is such 55 that change of direction is given to the passage of coal from the pocket to the discharge

so that the coal acquires but little momentum in its travel and is easily controlled and screened.

E is a cut-off adapted normally to close the outlet between the lower ends C¹ of the shelf and the screen D and control the discharge of coal. It has preferably a curved face which is attached to two arms e which are mounted upon a square portion of the shaft e¹ which shaft is mounted in bearings in the side walls of the chute. The shaft runs through the walls of the chute and at one end has a handle F attached to it. By moving this handle therefore the position of the gate is changed so as to open the outlet from the chute or close it as the case may be. This gate may be constructed in other ways, but the fact that its face is curved as described enables it to move up easily out of the way to allow the weight of coal in front of it to fall 75 out from the chute, and the face being thin, made like the other parts except the screen of sheet metal, easily finds its way back when it is desired to cut off the flow of coal from the chute.

Below the screen D the forward wall of the chute is brought outward as at B² to form the support for the guiding trough B³ onto which the coal is directed by the screen. The chute is provided at its lower end with 80 hinged doors B⁴. These doors are preferably hinged across the middle of the chute and are held closed against the opposite edge of the chute by catches b of any convenient form. A chamber B⁵ is thus formed to catch 85 the screenings from the coal. They may be discharged at any time by unlatching the doors B⁴ and allowing them to fall.

To support the upper end of the screen D I provide short angle irons d bolted to the 90 sides of the chute. The lower edge of the screen rests against an angle iron d² and the upper edge of the floor of the trough B³. When the parts are in the position shown in Fig. 1, the upper end of the screen and the 95 cut-off prevent the escape of coal from the chute. By lifting the cut-off the coal runs out, being screened as it passes over the screen, the screenings collecting in the bin. Soft coal is not screened. When therefore 100 this chute is used for soft coal the end C¹ of the shelf is removed by removing the bolts which hold it in place. The screen is removed and a shelf d¹ hinged at d² to the interior of the chute and normally raised and 105

buttoned by the button d^4 in its vertical position is lowered so that it rests upon the angle irons d and with the cut-off E closes the outlet from the chute. When soft coal is to be discharged the cut-off is lifted and the doors B^4 are opened so that the coal falls directly through the chute into the wagon or other receptacle below.

An advantage which attaches to this apparatus lies in the fact that it can be easily used for either of two purposes—for delivering soft coal or screening and delivering hard coal—and in the latter case the passage of the coal is so tortuous that the discharge of coal can be started and can be cut off easily at any moment no matter how much weight of coal there is behind it. Thus the apparatus can easily be managed by one man. It is also apparent that the instrumentalities shown may be differently arranged and that by a rearrangement certain of the elements may be consolidated, but the form shown is simple and as it seems to me, serves the desired purpose of affording both a screening and non-screening chute.

What I claim as my invention is:

1. A coal gate comprising a vertical chute, a shelf extending from one wall thereof towards the opposite wall to partially close its outlet whereby a narrow mouth is provided for the exit of the coal between the end of said shelf and said opposite wall, and means such as a screen lying under said mouth to change the direction of the coal issuing from said mouth and screen it, and a cut-off located within said chute for controlling the issue of coal from said mouth, as described.

2. A coal gate comprising a vertical chute, a shelf extending from one wall thereof towards the opposite wall to partially close its outlet whereby a narrow mouth is provided for the exit of the coal, and means such as a screen lying under said mouth to change the direction of the coal issuing from said mouth and screen it, and a cut-off located within said chute for controlling the issue of coal from said mouth, as described.

3. A coal gate comprising a vertical chute, a shelf extending from one wall thereof towards the opposite wall to partially close its outlet whereby a narrow mouth is provided for the exit of the coal between the end of said shelf and said opposite wall, and a removable screen located below said outlet and serving to carry off the larger coal and at the same time to screen therefrom the smaller particles and a cut-off located within said chute and adapted to coöperate with said shelf to close the outlet therefrom.

4. In a coal gate, a vertical chute, an extensible shelf extending outward from one wall towards the other wall to partially close its outlet and serve as a guide therefrom, a removable screen located below said shelf and extending from the opposite wall of said

chute to change the direction of movement of the coal and screen therefrom the smaller particles thereof.

5. In a coal gate, a vertical chute having an opening at one side, a shelf extending part way across said chute above said opening and partially closing the discharge opening from said gate, a swinging shelf adapted when in its lowest position to receive the coal from said outlet and change its direction and when in its upper position to make room for a screen, and means to support said shelf when in its lower position and to support said screen when said shelf is in its upper position, as described.

6. In a coal gate, a vertical chute having means for discharging coal laterally therefrom, means for providing said chute with a contracted outlet, and a cut-off located within said chute but outside of said contracted outlet and in close proximity thereto, said cut-off being constructed on a horizontal axis and having means whereby it may be turned about said axis as described.

7. In a coal gate, a vertical chute having means for discharging coal laterally therefrom, means for providing said chute with a contracted outlet comprising shelves supported from opposing walls of said chute, the one above the other, and a cut-off located in front of said outlet upon a horizontal axis and having means whereby it is operated, said cut-off comprising two approximately segmental arms and a curved connecting face as described.

8. A coal gate comprising a vertical chute, a shelf extending from one wall thereof towards the opposite wall to partially close its outlet whereby a narrow mouth is provided for the exit of the coal, a screen located below said outlet to screen the coal received therefrom, a discharge opening in one side of said chute to receive the coal screened by said screen, and a dust-chamber located below said screen and provided with a door on its under side, as set forth.

9. A gate for a coal pocket comprising a vertical chute, a shelf extending across the cross area of said chute and adapted to co-operate with the opposing wall thereof to form a narrow mouth for the exit of the contents of said chute, means located below said mouth whereby the direction of movement of the coal falling vertically through said mouth will be changed to a lateral direction, in combination with a cut-off located within said chute and near said mouth and adapted to control the exit of coal therefrom, as set forth.

10. A gate for a coal pocket in combination with a vertical chute, a shelf extending from one wall thereof into close proximity with the opposite wall whereby a narrow mouth is formed for said pocket, said shelf being provided with a detachable portion

whereby the said mouth may be enlarged, a shelf located below said mouth and adapted to change the direction of the coal flowing therefrom, and a gate located to control the flow of coal from said mouth, all as described.

11. A gate for a coal pocket comprising a vertical chute, a coal supporting shelf extending from one side of said chute nearly to 10 the opposite wall leaving an outlet between

it and said wall, a second shelf located below said outlet and adapted to direct the movement of coal therefrom, and a cut-off located within said chute and adapted to control the passage of coal through said outlet as described. 15
